Letters Patent No. 77,947, dated May 19, 1868.

IMPROVED TRUSS.

The Schedule referred to in these Letters Patent and making part of the same.

TO ALL WHOM IT MAY CONCERN:

Be it known that I, SAMUEL AYRES, of 64 Water street, in the city, county, and State of New York, have invented a new and useful Improvement in Trusses; and I do hereby declare the following to be a full, clear, and exact description thereof, which will enable those skilled in the art to make and use the same, reference being had to the accompanying drawing, forming part of this specification, in which drawing—

Figure 1 is a sectional view of a truss which contains my improvement.

Figure 2 is a section of a covered truss-pad.

This invention relates to an improvement in trusses for the relief and cure of ruptures. One of the features of the invention is making the pad of cork. Another feature consists in the mode of connecting the pad to the band or strap which encircles the person of the patient. The belt or strap of the truss is composed of the parts A A and B, consisting of webbing. The parts A A are joined to the part B at the points C C. The letter D designates the pad.

I make the same of cork, cut to the shape and size required, with a flange, E, surrounding it, from which flange the face of the pad rises on a curve, substantially as shown. One object of the flange is to produce a broad stop around the circumference or sides of the pad, which will, by coming against the body, limit the extent to which the prominent part of the pad can sink in the abdomen, and another object is to obtain a bearing-surface for the strap to act upon which shall be greater than the prominent operating-face of the pad.

Upon the back of the pad I form a loop, F, through which the belt or strap goes loosely, said belt or strap being free to slide therein, and accommodate itself to any position of the body without dragging the pad with it, and without interfering with the pad when adjusted in its proper place.

In fig. 2 I have shown a cork pad, covered with chamois leather, G. But a covering is not necessary for the cork pad. Pads can be made to conform, in shape and size, to the nature and peculiarity of each particular rupture, and when a rupture exists in each groin, another pad may be added to the same belt.

Among other advantages of my improvement of a cork pad are the following: That the said material is light and soft, a non-absorbent of exhalations from the skin, a non-conductor of the heat of the body, and is not liable to the objections found in wood, ivory, or the common stuffed pad, which latter soon becomes disagreeable by absorbing moisture from the body.

If the cork pad becomes foul, it is only necessary to detach and clean it with soap and water.

What I claim as new, and desire to secure by Letters Patent, is—

1. Connecting the pad of a truss with the band or strap by a loop, F, through which the belt slides loosely, substantially as described.

2. Making a truss-pad of cork, substantially as described.

3. The flange E, around the edge of the pad, substantially as described.

Subscribed by me, this fifth day of March, 1868, before two subscribing witnesses.

SAML. AYRES.
